UNITED STATES PATENT OFFICE

167,917

CUP

Franz Wagner, Chicago, Ill., assignor to Easterling China Company, Chicago, Ill., a corporation of Illinois

Application October 30, 1951, Serial No. 17,170

Term of patent 14 years

(CL. D44—9)

To all whom it may concern:

Be it known that I, Franz Wagner, a citizen of the United States, residing at Chicago, county of Cook, and State of Illinois, have invented a new, original, and ornamental Design for a Cup, of which the following is a specification, reference being had to the accompanying drawing, forming a part hereof.

Fig. 1 is a top plan view of a cup showing my new design;

Fig. 2 is a partial side elevational and partial vertical sectional view on line 2—2 of Fig. 1;

Fig. 3 is another side elevational view showing the cup rotated 90° with respect to Fig. 2;

The characteristic feature of my design for a cup resides in the handle portion in its association to and arrangement with the body portion of the cup.

I claim:

The ornamental design for a cup, as shown and described.

FRANZ WAGNER.
